UNITED STATES PATENT OFFICE

FRANK KRAEMER, OF BUFFALO, NEW YORK, ASSIGNOR, BY MESNE ASSIGNMENTS, OF
ONE-HALF TO THE UNITED STATES LABELING MACHINE COMPANY.

LABELING MACHINE.

1,170,913.

Specification of Letters Patent.

Patented Feb. 8, 1916.

Application filed April 13, 1914. Serial No. 831,459.

To all whom it may concern:

Be it known that I, FRANK KRAEMER, a citizen of the United States, residing at Buffalo, in the county of Erie and State of New York, have invented new and useful Improvements in Labeling-Machines, of which the following is a specification.

This invention relates to a machine designed more especially for applying labels to bottles containing beverages, such as beer and soft drinks, but the same is also useful for labeling other receptacles of similar form.

The object of my invention is the production of a compact and reliable machine by which such bottles and similar containers can be labeled expeditiously and at much less cost than by manual labor.

In the accompanying drawings: Figure 1 is a side elevation of a machine embodying the invention. Fig. 2 is a sectional top plan view thereof. Fig. 3 is a longitudinal section of the machine on line 3—3, Fig. 4, Fig. 4 is a transverse section on line 4—4, Fig. 3. Figs. 5 and 6 are fragmentary longitudinal sections on the correspondingly numbered lines in Fig. 4. Fig. 7 is a longitudinal central section of the label-feeding and pasting mechanism, on an enlarged scale. Fig. 8 is an end view thereof. Fig. 9 is a horizontal section on line 9—9, Fig. 7. Fig. 10 is a transverse section on line 10—10, Fig. 7. Fig. 11 is a fragmentary longitudinal section on line 11—11, Fig. 8. Fig. 12 is a transverse section of the follower-screw on line 12—12, Fig. 7.

Similar characters of reference indicate corresponding parts throughout the several views.

The main frame of the machine comprises a base 1, upright longitudinal side plates or frames 2, 3, mounted on the base. In the preferred construction shown in the drawings, one of these side frames is fixed to the base, while the opposite frame 3 is movable toward and from said fixed frame to render the machine adjustable to bottles of different lengths. For this purpose the movable side frame is provided with an extended foot 4 which is adjustably secured to the base 1 by vertical clamping bolts passing through said foot and through slots 5 arranged transversely in the base of the machine. The side frames are connected at

their ends by a pair of overlapping or telescopic bars 6 carried by the frames respectively and adjustably clamped together by bolts 7 passing through openings in one of the lapped bars and horizontal slots 8 in the other bar, as best shown at the left-hand end of Fig. 2.

9 indicates a conveyer or carrier, preferably of the endless type, extending horizontally from the front to the rear end of the machine and adapted to present the bottles 65 successively to the bottle-rotating and label-applying mechanism hereinafter described. The conveyer shown in the drawings consists of comparatively wide links 10 pivotally connected by pintles 11 carried by sprocket chains 12 which pass around sprocket wheels 13 secured to the front and rear shafts 14 mounted in the side frames 2 and 3. In the construction shown in the drawings, the front shaft is adjustable relatively to the rear one for taking up any slack or wear of the conveyer. For this purpose, the front shaft is carried by bearing boxes 15 sliding in longitudinal slots 16 of said side frames and the shaft is adjusted, to tighten the conveyer, by longitudinal screws 17 secured at their ends to sleeves 18 loosely surrounding the shaft. The outer portions of the screws are slidable in bearings 19 carried by the outer of the overlapping end bars 6. At their outer ends the screws have adjusting nuts 20 which bear against said end bar, whereby upon turning the said nuts in one or the other direction, the front shaft of the conveyer 14 is 90 adjusted toward or from the rear one. Each of the conveyer-links 10 carries a pair of opposing bottle-seats or saddles 21 which may be longitudinally adjustable on the plates to enable them to be placed in accurate alignment transversely of the chain. This may be done by means of clamping bolts 22 tapped into the links and passing through longitudinal slots in the base flanges of the saddles, as shown.

23 indicates the main shaft of the machine supported transversely in the side frames 2 and 3 and passing between the upper and lower runs of the conveyer. This shaft may be driven by an electric motor 24 having its armature shaft 25 provided with a worm which engages a worm gear or disk 26 secured to the main shaft 23. One of

the conveyer shafts 14 is driven from this main shaft by a sprocket chain 27 and sprockets 28. The worm gear or disk 26 is arranged adjacent to one side of the endless conveyer and carries on its inner face a circular series of equidistant rotary holders 29 against which the bottoms of the bottles to be labeled are seated. The bottles are pressed against these holders by a corresponding series of spring-pressed plungers or holders 30 arranged in alinement therewith and bearing against the heads or mouths of the bottles, as best illustrated in Fig. 4, in which one of the bottles is shown by dotted lines. These plungers are carried by a rotary disk 31 secured to the main shaft 23 at the side of the conveyer opposite that at which the gear-disk is located. Each of these plungers is free to turn and slide in a transverse socket 32 of the disk 31 and provided with a reduced stem 33 extending through the outer end of the socket and terminating in a head or button 34.

35 indicates the plunger-spring which preferably surrounds said stem between the plunger and the closed end of the socket, as shown in Fig. 4.

Referring to the last-named figure, each of the rotary bottle-holders 29 has a hollow spindle 36 suitably journaled in the gear disk 26 parallel with the axis of the latter. Fixed to the projecting outer end of this spindle is a pinion 37 which during a portion of the rotation of said disk is adapted to engage a fixed gear segment 38 secured to the adjacent side frame 2 concentrically with said disk, so that the pinions 37 by successively rolling over said segment, rotate the bottle-holders 29 and the bottles seated 40 against them. In the preferred construction shown, this gear segment forms the upper portion of a ring 39, the remaining portion of which is smooth or toothless and offset outwardly beyond the segment, as shown in Fig. 4. The spindle of each bottle-holder 29 is provided at its outer end with a smooth edged stop wheel or pinion 40 provided in its periphery with opposing concave notches 41, one or the other of which is adapted to engage the smooth edge of said ring 39, to hold the bottle-holder and the bottle clamped against it against turning while out of engagement with the gear-segment. By this construction, the bottle-holders are at rest 55 at the times that they receive the bottles from the conveyer and deliver them thereto, avoiding liability of displacing the bottles from their proper position as they enter and leave the bottle-holders, which might otherwise occur.

In order to reliably center the bottles on their bottom-holders 29 when delivered thereto by the conveyer, a pair of centering rollers 42 are arranged at opposite edges of the holder, as best shown in Fig. 3, these

rollers being journaled on studs secured to the inner side of the gear disk 26 parallel with the spindles of said holders. One of the centering rollers of each holder is located below a line passing diametrically 70 through the axis of the holder and the other centering roller, referring to the position of the holder as it ascends on the receiving side of the rotary disks 31.

To insure the proper centering of the 75 heads of the bottles against the plungers 30, suitable centering seats or bars 43 are mounted on the disk 31 in the proper position to receive and support the necks of the bottles as the latter enter between the plungers and the holders, as shown in Figs. 4 and 5. One of these bars is employed for each bottle and it is supported at a suitable distance from the disk by rods 44 projecting inwardly therefrom. As shown in Fig. 5, 85 the outer portions of these bars are curved on their front sides to conform to the necks of the bottles.

Automatic means are provided for withdrawing the plungers 30 to receive the bottles between them and the rotary holders 29, and similar means are provided for withdrawing the plungers to release the bottles after receiving the labels. The preferred means shown in the drawings consist of a 90 receiving cam 45 arranged in the path of the inner sides of the plunger buttons 34 at the front or bottle-receiving side of the rotary disks 31 and a similar releasing or discharge-cam 46 likewise arranged in the path 95 of said buttons at the rear or bottle-discharging side of said disks. The outer faces of said cams are oblique to draw the plunger-buttons 34 outwardly against their springs 35 and withdraw the plungers to a position 10 in which the bottles may enter freely between them and the rotary holders 29 at the receiving side of the disks 31 and be released therefrom at the discharge side of the disks where the labeled bottles are again received 11 by the conveyer and deposited upon a platform or other suitable support, not shown in the drawings. In the construction shown, these cams are carried by a bracket 47 secured to the adjacent side frame 3 of the 11 machine.

48 indicates a table or support arranged at the front end of the machine over the upper side of the conveyer 9 and adapted to receive the bottles to be labeled which are placed thereon by an attendant. This table extends rearwardly to the front side of the disks 26, 31, and is slotted longitudinally from a point near its front end to its extreme rear end, as shown at 50, to permit the bottle-saddles 21 to project through the table on arriving at the upper side of the conveyer. This table has side walls or guides 51 which prevent endwise displacement of the bottles on the saddles and ar-

ranged in alinement with the faces of the bottle holders 29 and the plungers 30, so as to guide the bottles between them.

Mounted above the space between the disks 5 26, 31 is a suitable label feeding and pasting mechanism illustrated in Figs. 7-12, which is preferably constructed as follows:

52 indicates a box or casing which is suspended from a pair of cross bars 53 supported by supplemental side frames 54 surmounting the main side frames 2, 3, and rigidly secured thereto. To permit one of those supplemental side frames to follow the lateral adjustment of the corresponding main side 15 frame 2, the cross bars are secured to said frame by clamping bolts 55 passing through longitudinal slots in the bars, as shown in Fig. 2.

Arranged in the upper portion of the casing 20 is a longitudinal label compartment 56 in which the labels are stacked on end. Resting on the bottom of this compartment is a follower 57 which bears against the back of the stack of labels and serves to feed them 25 against an abutment 58 forming the front wall of the compartment and terminating short of the bottom. This abutment is arranged in line with the front side of a transverse feed roll 59 arranged in such close 30 proximity to the front edge of the bottom as to allow but a single label to pass at the time. The abutment 58 is preferably yieldable and for this purpose is mounted to slide on longitudinal guide rods 60 carried by the side 35 walls of the box 52, and springs 61 are applied to these rods between the abutment and supporting lugs of said guide rods, as shown in Figs. 7 and 8.

The follower 57 is intermittently fed forward by any suitable means but I prefer to employ for this purpose a non-rotary screw 62 arranged in a socket 63 projecting from the back of the follower and sliding in the smooth bored hub of a worm-wheel 64 journaled in the rear wall of the label compartment and in a standard 65 secured to the bottom of the compartment, the worm wheel being held against endwise movement between said parts but free to turn therein. 40 Its hub projects beyond said wall and is provided with a radial opening in which is guided a pin 67 adapted to engage the thread of the screw 62, so that when said pin engages the screw and the worm wheel is turned in the proper direction, the screw is caused to slide in the hub of the worm wheel and move the follower 57 toward the front wall of the label compartment. The pin 67 is carried by the free end of a C-shaped spring 68 which surrounds the extended end of the worm wheel hub and is fixed at its other end to said hub, as shown at 69 in Fig. 14; this spring normally holding the pin in engagement with the thread of the follower screw. When the follower reaches

the limit of its forward movement, it can be readily pushed back to its initial position for re-filling the label-box by simply withdrawing the pin 67 from the screw, the screw sliding freely through the worm-wheel hub. 70 It is desirable that the follower should exert a yieldable pressure against the stack of labels, and for this purpose the follower socket 63 is mounted to slide to a limited extent on the screw 62 and a spring 70 is 75 interposed between the inner end of the socket and the front end of the screw, these parts being connected by a screw 71 carried by the follower-screw and passing through a longitudinal slot 72 of said socket, or by 80 other suitable means.

By making both the follower and the abutment 58 yieldable, excessive compression of the interposed labels is avoided, insuring the reliable feeding of a single label at a time. 85

73 indicates a worm meshing with the worm wheel 64 and mounted on a transverse shaft 74 supported in the side wall of the label-compartment. This shaft is driven from an intermittently-rotating clutch gear 90 75 through the medium of a sprocket chain 76 running around sprocket wheels 77 mounted on said shaft and on the hub of an idler pinion 78 which in turn meshes with said clutch gear, as shown in Figs. 1, 2 and 10. 95 This clutch gear is mounted on a hollow stud 79 carried by the box 52 and is adapted to be connected by a suitable clutch with a continuously-rotating shaft 80 journaled in said box. The last-named shaft is driven 100 by a sprocket chain 81 from a countershaft 82 which in turn is driven from the main shaft 23 by a sprocket chain 83. Said clutch may be of any suitable construction, that shown in the drawings consisting of a sleeve 105, 84 mounted to slide lengthwise on the projecting end of the shaft 80 and having radial pins 84¹ adapted to interlock with pins 85 projecting from the outerside of the clutch gear. The clutch-sleeve is normally held out 110 of engagement with the clutch gear by a spring 86 and moved into engagement therewith by a cam or incline 87 carried by a vertically-reciprocating cam rod 88. The clutch-sleeve is compelled to turn with the 115 shaft 80 by a cross pin 89 which engages the forked end of said shaft. As shown in Fig. 10, the clutch-gear 75 is mounted concentrically with its actuating shaft 80.

Arranged below the discharge end of the 120 label-compartment are a pair of lower feed rolls 90, 91, which are adapted to receive between them the labels successively fed downward by the upper feed roll 59. These three feed rolls are journaled in the side 125 walls of the box 52 and the upper roll and the feed roll 90 immediately thereunder are both intermittently rotated in unison by spur gears 92, 93 mounted on their respective shafts and both meshing with the clutch gear 130

75, as best shown in Fig. 1. The lower rear feed roll 91 is constantly rotated from a gear 80^a on the continuously-turning shaft 80 by a gear 94 mounted on said roll-shaft and an intermediate idler 95, as shown in Fig. 10. Also mounted on the last-named roll shaft are a pair of paste-wheels 96 which are preferably arranged to apply paste or other adhesive material along the marginal portions of the labels as they pass between the lower rolls 90, 91. These paste wheels are respectively arranged in a pair of paste-receptacles or chambers 97 which may be formed integral with the box 52 but are preferably formed in a drawer 98 suitably guided on said box, so that it may be removed to conveniently clean the paste-receptacles from time to time.

99 indicates wiping rolls arranged below the lower feed roll 90 in the proper position to bear against the advancing sides of the rotating bottles as they are carried past the label-feeding and pasting mechanism by the rotary disks 26, 31. For this purpose, said wiping rolls are preferably carried by a pair of hangers 100 pivoted on the shaft of the lower front feed roll, so as to be free to swing lengthwise of the machine. The shafts of these wiping rolls are mounted at their ends in substantially upright rock bars 101 preferably pivoted centrally upon a horizontal rod 102 mounted in the lower ends of said hangers, so that the wiping rolls are free to accommodate themselves to the cylindrical surface of the bottles and smoothly press the pasted label against the same. The wiping rolls are yieldingly held in their righted or operative position against the bottle by a suitable spring. In the construction shown, Figs. 8 and 11, a wire spring 104 is employed which is fastened at its upper end to the inner side of one of the hangers and bears at its free lower end against a lug 105 secured to the adjacent carrying-bar 101 of the rolls and extending above and below the pivot-rod 102. By this construction, the spring resists rocking or tilting of such bars out of their normal position. The wiping rolls bear against the side of the bottle by gravity, and after receiving its label the advancing bottle pushes the wiping rolls rearwardly and passes under them, the suspended rolls swinging back to their normal position by the time the next bottle arrives under the label-feeding mechanism.

107 indicates a pair of label-guides arranged slightly in rear of the meeting edges of the lower feed rolls 90, 91, and extending downwardly to a point opposite the upper wiping roll 99, so as to guide the descending label between the wiping rolls and the bottle. 108 indicates suitable scrapers which serve to remove the excess paste from the paste-wheels 96, and which may be carried by the removable drawer 98.

As before stated, the label-advancing follower 57 and the feed rolls 59, 91 are actuated intermittently; this being necessary in order to prevent the feeding of labels during the intervals that no bottles are presented to the label-feeding mechanism. This intermittent operation of the feeding mechanism must have a definite relation to the movement of the bottle-carrying disks 26, 31. The proper relative timing of these movements is effected by trip pins 109 guided axially in the bottle-holders 29 and adapted to be engaged by the bottoms of the bottles seated against the holder. These pins are of such length that when a bottle is fed between one of the holders and its companion plunger 30, the corresponding trip pin is projected beyond the outer side of the gear disk sufficiently to engage a shoe 110 at the lower end of the cam rod 88 when the bottle arrives in the proper position under the label feeding mechanism to receive a label therefrom, as shown by dotted lines in Fig. 7. When such a trip pin encounters the shoe, it pushes said rod upward, causing its cam 87 to shift the clutch sleeve 84 into engagement with the clutch gear 75 and driving the sprocket wheels 77 momentarily and at the same time driving the worm gear 73 to cause the screw 62 to advance the follower 95 a step, the duration of these movements being sufficient to feed the foremost label of the stack down past the pasting wheels 96 and between the topmost bottle and the wiping rolls 99. As soon as the active trip pin 109 clears said shoe 110 by the forward rotation of the gear disk, the cam-rod is depressed to its initial position by a spring 112, Fig. 8, allowing the spring 86 to throw the clutch sleeve out of engagement with the clutch gear, and stopping the feed roll 90 until the trip pin of the next succeeding bottle-holder 29 strikes the shoe when the label-feeding and pasting mechanism is again actuated.

The trip pins 109 are held frictionally in the bores of the bottle holders 29, and their faces should be normally flush with the faces of the bottle holders, otherwise they will interfere with the free entrance of the bottles between them and the companion plungers 30. To always insure the retraction of the trip pins, a spring or equivalent part 113 is arranged in the circular path of travel of the trip pins, so that by the rotation of the gear disk 26, the bottle-holders ride or brush over this spring, which pushes any inwardly-displaced pins outward so that their inner ends are flush with the faces of the bottle holders. In the construction shown in the drawings, this retracting spring is carried by a bracket 114 secured to the adjacent side frame 2 of the machine.

It may sometimes happen that a pair of opposing bottle-holders and plungers 30 are 130

empty, and in order to prevent the operation of the label-feeding mechanism when such an empty pair arrives opposite it, a trip-spring or member 115 is located in the proper position to be encountered by the projecting outer end of the trip pin 109 of the empty bottle-holder before said pin reaches the shoe of the cam rod 88. Said trip pin is thereby pushed inward far enough to clear the shoe, preventing actuation of the cam rod and avoiding waste of a label which would otherwise occur. This trip spring may be supported by any suitable means but is preferably carried by the shoe 110; as shown in Figs. 1 and 4.

It will be understood that the length of the shoe determines the time of operation of the labeling and pasting mechanism, a larger or shorter shoe being employed according to the size of the labels to be applied to the bottles. The pinions 37 of the rotary bottle-holders have a sufficient number of teeth to turn the bottles.

When labels of maximum length are employed, or such as have overlapping ends, the bottles must obviously be given more than a complete turn, say a turn and a half. For this purpose, each pinion has a smaller number of teeth than a section of the gear-segment equal to the distance between the axes of two adjacent pinions. In practice such a section may have 36 teeth and the pinions 24 teeth. It is also obvious that in practice the distance between adjacent bottle-holders must be equal to the distance between adjacent bottle-seats of the conveyer, and that the latter and the rotary disks 26, 31 must travel in unison.

Where bottles have the name and address of the manufacturer or other matter embossed on one side thereof, it is necessary to apply the labels on the opposite, smooth side, and the bottles must be placed in the conveyer-seats 21 with their embossed sides downward. To permit such bottles to be placed at random in the conveyer-seats and yet insure the presentation of their unembossed sides to the labeling mechanism, I provide means for automatically turning them to their proper position. The preferred device comprises one or more brushes or wipers 116 arranged above the path of travel of the embossed bottom-portions of the bottles which overhang the side of the conveyer. These brushes may be located near the receiving end of the conveyer and their lower edges are so arranged that they clear or barely touch the unembossed portions of the bottles passing under them, but are encountered by the embossed portions thereof, compelling the traveling bottles to turn in their seats until their embossed portions arrive under the brushes, when the bottles are carried around toward the labeling mechanism with their smooth side upward.

The brushes may consist of relatively stiff rubber strips secured in suitable brackets or holders 117 carried by the feed table or other support.

The machine being set in motion, its operation is as follows: The conveyer 9 and the rotary disks 26, 31 travel constantly in the direction of the arrow, the label-follower 57 and upper and lower feed wheels 59, 91 operate intermittently, and the paste wheels 96 rotate constantly to agitate the paste and prevent thickening thereof. The unlabeled bottles placed upon the table 48 are successively deposited in the seats 21 of the conveyer and when a bottle enters between the disks 26, 31, it is met by one of the head centering seats 43 and an opposing pair of bottom centering rollers 42 which lift the bottle from the conveyer-seat and center it between the corresponding rotary bottle-holder 29 and plunger 30, the latter having been previously withdrawn by the front cam to admit the bottle. In the same manner, the succeeding bottles are transferred from the conveyer to the bottle holders and plungers of said disks or carriers. The moment one of the traveling bottles comes in contact with the wiping rollers 99, the projecting pin 109 of the corresponding bottle holder trips the shoe 110, throwing the label follower and the rotating feed rolls 59, 91 into gear with their driving mechanism and causing these parts to feed the foremost label of the stack past the paste-wheels and between the bottle and the wiping rollers, the advancing end of the label adhering to the bottle which by its rotation wraps the label about itself, while the wiping rollers press it smoothly against the bottle, completing the labeling operation. The traveling bottle pushes the wiping rollers aside and upon descending to a position immediately over one of the bottle-seats of the conveyer is automatically released by the withdrawal of the plunger 30 and deposited on said seat, whereupon it is conveyed to the delivery end of the machine where it is removed by any suitable means. It will thus be seen that the labeling operation is entirely automatic, and as the conveyer and the rotary bottle-carriers and disks 26, 31 travel continuously, the machine has a correspondingly large capacity. At the same time, the machine is reliable in operation and comparatively simple and compact in construction.

When constructed as shown in the drawings, the machine can be adjusted to vary the distance between the opposing disks or bottle carriers to accommodate bottles of different lengths. This is accomplished by adjusting the side frame 2 toward or from the opposite frame, as hereinbefore described, and correspondingly shifting the adjacent plunger-carrying disk on the main shaft 23 upon which it may be adjustably

secured by a set screw 118. This main shaft is extended beyond said movable side frame for this purpose, as shown in Figs. 2 and 4. To facilitate this adjustment, the driving mechanism of the various parts is located wholly or principally on the opposite side of the machine, adjacent to its fixed side frame.

Various changes or modifications of parts 10 of the machine can obviously be made within the scope of the appended claims, and I do not therefore wish to be limited to the particular construction of the machine herein shown and described.

15 I claim as my invention:

1. In a labeling machine, the combination of a label-feeder, a rotary carrier coöperating therewith, a circular row of rotary bottle-holders mounted on said carrier, means 20 for turning said bottle-holders relatively to said carrier, and bottle-centering rollers journaled on the carrier at opposite sides of each of said holders.

2. In a labeling machine, the combination 25 of a label-feeder, opposing rotary carriers coöperating therewith, a circular row of rotary bottle-holders journaled in one of said carriers, an opposing row of spring-pressed plungers mounted in the other carrier, and 30 centering seats for the bottle-necks mounted on the inner side of the last-named carrier.

3. In a labeling machine, the combination 35 of a label-feeder, spaced rotary carriers coöperating therewith, a circular row of rotary bottle-holders mounted on one of said carriers, an opposing row of corresponding bottle-holders mounted on the other carrier, means for automatically turning said rotary 40 holders relatively to their carrier, and a conveyer running between said carriers and having bottle-seats.

4. In a labeling machine, the combination 45 of a label-feeder, spaced rotary carriers coöperating therewith, a circular row of rotary bottle-holders mounted on one of said carriers, an opposing row of corresponding bottle-holders mounted on the other carrier, automatic means for turning said rotary holders relatively to their carrier, bottle-centering 50 seats mounted on said carriers adjacent to said bottle-holders, and a conveyer arranged between said carriers and having bottle-seats.

5. In a labeling machine, the combination 55 of a label-feeder, mechanism for intermittently actuating the feeder, a carrier having bottle-holders, and trip means mounted on said carrier and coöperating with said actuating mechanism to operate the label-feeder 60 when a bottle arrives opposite the same.

6. In a labeling machine, the combination 65 of a label-feeder, mechanism for intermittently actuating the feeder, a carrier having bottle-holders, and trip pins mounted on said carrier coincident with the axes of said hold-

ers and coöperating with said actuating mechanism.

7. In a labeling machine, the combination of a label-feeder, mechanism for intermittently actuating the feeder, a carrier having 70 bottle-holders, trip pins slidable axially through said holders and controlling said actuating mechanism, and automatic means for shifting said pins lengthwise in said holders.

75 8. In a labeling machine, the combination of a label-feeder, mechanism for intermittently actuating the feeder, a carrier having said holders and controlling said actuating mechanism, and relatively fixed means arranged to be encountered by the inner ends 80 of said pins for shifting them flush with the faces of said holders.

9. In a labeling machine, the combination of a label-feeder, mechanism for intermittently actuating the feeder, a carrier having bottle-holders, trip devices retractably mounted in said bottle-holders and controlling said actuating mechanism, said trip devices being held in their normal projecting 90 position by the bottoms of the bottles seated against said holders, and automatic means for shifting said trip devices to their inoperative position when the holders are empty.

95 10. In a labeling machine, the combination of a label-feeder, mechanism for intermittently actuating the feeder, a carrier having bottle-holders, trip devices retractably mounted in said bottle-holders and controlling said actuating mechanism, said trip devices being held in their normal projecting position by the bottoms of the bottles seated against said holders, automatic shifting means arranged at the receiving side of 100 said carrier for moving said trip devices into operative position, and automatic shifting means arranged between the first-named shifting means and the label-feeder for moving the trip devices of empty bottle holders to inoperative position.

11. In a labeling machine, the combination of a label-feeder, mechanism for intermittently actuating the feeder, a carrier having bottle-holders, trip pins slidable axially in said bottle-holders and controlling said 115 actuating mechanism, and a cam-spring arranged in the path of travel of the projecting ends of said pins for shifting the pins of empty bottle-holders out of operative position.

12. In a labeling machine, the combination of a label-feeder, driving mechanism, a clutch for connecting the feeder with said driving mechanism, a cam-member controlling said clutch, a rotary carrier, bottle-holders mounted at intervals on the carrier, and trip pins mounted on said carrier coincidently with said bottle-holders and arranged to engage said cam-member.

13. In a labeling machine, the combina- 120

- tion of a label-feeder, driving mechanism, a clutch for connecting the feeder with said driving mechanism, a spring-pressed cam-rod controlling said clutch and having a shoe, a rotary carrier having bottle-holders, and trip pins located in said bottle-holders and arranged to engage said shoe.
14. In a labeling machine, the combination of a label-feeder, opposing carriers, 10 rotary bottle-holders mounted on the inner side of one of said carriers, opposing bottle-holders mounted on the other carrier, a bottle-conveyer running between said carriers, and a feed-table having side walls arranged 15 in line with the faces of said opposing bottle-holders for guiding the bottles between them.
15. In a labeling machine, the combination of a base, side frames mounted thereon, 20 one of said frames being adjustable toward and from the other, a transverse shaft supported in said frames, a pair of opposing bottle-carriers mounted on said shaft, one of said carriers being adjustable relatively to 25 the other to accommodate bottles of different lengths, bottle-holders mounted on the opposing sides of said carriers, and means for affixing labels to the bottles.
16. In a labeling machine, the combination 30 of a conveyer having bottle-seats, a bottle-rotating brush located at one side of the conveyer and arranged to engage embossments on the upper sides of the bottles occupying said seats, and means coöperating 35 with said conveyer and arranged to apply labels to the bottles after being turned by said brush means.
17. In a labeling machine, the combination of a bottle carrier, a label-box arranged above said carrier and having a discharge 40 opening, label-feeding means arranged at said opening, hangers arranged below said feeding means, bars pivoted between their ends to said hangers, and wiper-rolls journaled on said bars on opposite sides of their 45 pivot.
18. In a labeling machine, the combination of a bottle carrier, a label box arranged above said carrier and having a discharge 45 opening, label-feeding means arranged at said opening, a pivoted hanger suspended below said feeding means, bars mounted to swing on said hangers, and wiper rolls journaled on said bars one above the other.
19. In a labeling machine, the combination 50 of a bottle carrier, a label box arranged above said carrier and having a discharge opening, label-feeding means arranged at said opening, a hanger suspended below said feeding means, opposing bars mounted to 55 swing on said hanger, one of said bars having a righting lug, a spring bearing against said lug, and a wiper roll journaled in said bars.

Witness my hand this 10th day of April, 65
1914.

FRANK KRAEMER.

Witnesses:

C. F. GEYER,
E. M. GRAHAM.

It is hereby certified that in Letters Patent No. 1,170,913, granted February 8, 1916, upon the application of Frank Kraemer, of Buffalo, New York, for an improvement in "Labeling-Machines," errors appear in the printed specification requiring correction as follows: Page 6, line 78, claim 8, after the word "having" insert the words *bottle-holders, trip pins slidable axially in*; page 7, line 38, claim 16, strike out the word "means;" and that the said Letters Patent should be read with these corrections therein that the same may conform to the record of the case in the Patent Office.

Signed and sealed this 29th day of February, A. D., 1916.

[SEAL.]

R. F. WHITEHEAD,

Acting Commissioner of Patents.

Cl. 216—59.
